UNITED STATES PATENT OFFICE

2,487,464

SPREADER STOKER APPARATUS

Donald J. Mosshart, Ardmore, Pa., assignor to
Westinghouse Electric Corporation, East Pitts-
burgh, Pa., a corporation of Pennsylvania

Application August 17, 1944, Serial No. 549,848

6 Claims. (Cl. 110—115)

1

This invention relates to stokers, more particularly to those of the "sprinkler" or "spreader" type, and has for an object to provide improved apparatus of this character.

Yet another object of the invention is to provide spreader stoker mechanism having a plurality of rams for feeding fuel to the rotary impeller, together with means for imparting reciprocatory motion to each of the rams in such a manner that each ram reciprocates out of phase with respect to the adjacent rams.

Yet another object of the invention is to provide, in a spreader stoker, ram structure for feeding fuel rearwardly over a spill plate structure, together with means for reciprocating the latter in order to vary the front-to-rear location of the rear discharge edge of said spill plate structure with respect to a rotary impeller positioned therebeneath.

A further object of the invention is to provide, in a spreader stoker having reciprocating spill plate mechanism, means for varying the length of travel of the spill plate, and for varying the position of such travel with respect to rotary fuel impelling mechanism to change the front-to-rear location of the point of fuel discharge from the spill plate.

Yet another object of the invention is to provide, in spreader stoker mechanism, a plurality of spill plates disposed in side-by-side relation, together with means for imparting to said spill plates reciprocatory motion of such a nature that the reciprocation of each spill plate is out of phase with that of the adjacent spill plates.

Yet another object of the invention is to provide, in a stoker mechanism of the spreader or sprinkler type, ram structure for feeding fuel rearwardly over a spill plate structure for discharge from the latter to a rotary impeller positioned therebeneath, together with a power-operated shaft and means providing a driving connection between the latter and the ram structure and the spill plate structure for imparting the reciprocatory motion to said structures.

These and other objects are effected by the invention as will be apparent from the following description and claims taken in connection with the accompanying drawings, forming a part of this application, in which:

Fig. 1 is a longitudinal sectional view through spreader stoker apparatus embodying the principles of the present invention, portions thereof being broken away for the sake of clearness;

Fig. 2 is a fragmentary side elevational view of the structure shown in Fig. 1;

2

Fig. 3 is a plan view of the apparatus shown in Fig. 1, portions thereof being broken away for the sake of clearness;

Fig. 4 is a sectional view taken along the line IV—IV of Fig. 1, looking in the direction indicated by the arrows, a portion of the casing being omitted for the sake of clearness;

Fig. 5 is a sectional view taken along the line V—V of Fig. 4, looking in the direction indicated by the arrows;

Fig. 6 is a sectional view taken along the line VI—VI of Fig. 1, looking in the direction indicated by the arrows;

Fig. 7 is a diagrammatic representation of the driving connection between the stoker engine and the spill plate structure;

Fig. 8 is a view similar to Fig. 3, showing a modification of the spill plate structure; and

Fig. 9 is a sectional view taken along the line IX—IX of Fig. 8, looking in the direction indicated by the arrows.

Referring now to the drawings more in detail, particularly to Fig. 1 thereof, the reference character 10 indicates, in its entirety, a stoker of the spreader or the sprinkler type comprising a hopper 11, from which fuel is adapted to be fed to a ram box 12, disposed therebelow and in which a plurality of rams 13, 14 and 15 are adapted to reciprocate and to push fuel rearwardly over a spill plate 17, having a rear discharge edge 18 from which the fuel falls to the rotary fuel impeller, indicated, in its entirety, by the reference character 19.

Throughout the specification the direction "rearward" means from left to right in Figures 1, 2 and 3, and the direction "forward" means from right to left in those figures.

The rotary fuel impeller 19 comprises a drum 20, supported by radially-extending arms 21, carried by the sleeve portion 22 on the rotary shaft 23, the latter being supported by suitable bearings 24 (Fig. 4). The rotary impeller may be driven by any suitable source of power (not shown), through suitable means such as the belt 26 and associated pulley 27. The drum 20 is preferably provided with a pair of diametrically disposed, relatively long blades 28 and a second pair of diametrically disposed shorter blades 29 which, when the impeller is rotated clockwise as in Fig. 1, will impel fuel, falling from the rear discharge edge 18 of the spill plate 17, rearwardly through the opening 34 in the front wall 35 of the furnace, to the interior of the latter.

If desired, an equalizing plate or bar 31, carried by a reciprocable rod 38, having a plurality

of ribs 39 on its forward face, may be provided adjacent the rear discharge edge of the spill plate structure. The rod 38 is adapted to be reciprocated by suitable means (not shown) with the result that ribs 39 on the forward face of the plate 37 rub against the fuel being fed rearwardly by the rams and spread the fuel discharging over the rear edge of the spill plate. Such a device is particularly desirable where the fuel being fed is wet or frozen and would otherwise tend to fall from the spill plate in relatively large chunks or masses.

The lower wall 41 of the ram box 12 is preferably provided with a depending portion 42 having formed therein a transversely-extending chamber 43, to which suitable elastic fluid, for example, steam or air, may be admitted under pressure. The chamber 43 is provided with a transversely-extending series of openings 44 providing for rearward discharge of a stream or curtain of the air or steam beneath the rear discharge edge of the spill plate to either supplement the action of the rotary impeller, or to take the place thereof during failure of the impeller action for any reason.

In the arrangement herein illustrated, a steam engine 50 is mounted on suitable supporting structure at the front of the furnace, beneath the spreader mechanism heretofore described, and includes the usual piston rod 51 which, as illustrated in Fig. 4, is provided with an extension 52 reciprocable in bearings 53 and 54 carried by the supporting frame 55. A sleeve 57 is fixed upon the extension 52 and carries a bifurcated lug 58 to which one end of the link 59 is pivoted at 61 to the bifurcated free end 62 of an arm 63, fixedly secured to the inclined oscillatory shaft 64, the latter being supported at its lower end by the bearing 66 and at its upper end by the bearing 67, the former being secured to the furnace front wall and the latter to the under surface of the ram box structure 12.

A bevel gear segment 68 is fixed on the upper end of the inclined shaft 64 and meshes with a second bevel gear segment 69, secured to the lower end of the vertical shaft 70, whereby reciprocation of the steam engine piston rod 51 oscillates the vertical operating shaft 70.

As best shown in Fig. 3, a double crankarm 71 is secured at its mid-point to the vertical shaft 70 and has its ends connected through links 72 and 73 with the rams 13 and 14, respectively. The vertical shaft 70 likewise carries a crankarm 74 whose free end is connected through the link 76 with a corresponding crankarm 77 fixed to the vertical shaft 78. Oscillation of the vertical shaft 78 operates through the crankarm 79 and the link 80, which link is connected at one end to the crankarm 79 and at the other end to the ram 15, to oscillate said ram in unison with the ram 13. Thus, it will be apparent that, as the rams 13 and 15 move rearwardly, the intermediate ram 14 will be moving forwardly, and vice versa.

Reciprocatory motion is imparted to the spill plate structure by the mechanism now to be described. The bevel gear segment 69, carried by the vertical shaft 70, drives a third bevel gear segment 85, fixedly secured on the shaft 86, which shaft carries a crankarm 87 connected by links 88 and 89 with the pawls 90 and 91, respectively, of the double-acting and ratchet pawl mechanism 92. The ratchet wheel 93, which is acted upon by the pawls 90 and 91 for rotation in counter-clockwise direction as viewed in Fig. 1, is rotatably mounted upon the horizontal shaft 94 and has

eccentrically mounted on one face thereof the strap 95 which, in turn, is pivoted at 96 to a crankarm 97, fixedly secured on the shaft 98.

Referring now to Fig. 2, the shaft 98 extends outwardly through the side casing 33 and has fixedly mounted on its outwardly-extending portion a triangularly shaped arm 100. To the upper free end 101 of this arm a second arm 102 is pivotally connected by means of the bolt 102a. The second arm 102 is provided with an elongated arcuate slot 103, extending lengthwise thereof and in which is mounted a slidable block having a pivotal connection 104, for one end of a connecting link 105 whose other end has a fixed pivotal connection at 106 with the free end of the arm 107, fixedly secured on an end of the shaft 94, which extends outwardly through the side wall casing 33.

The pivotal connection 104 of the arm 105 with the slot 103 may be adjusted along the latter from one end thereof to the other by means of the screw 108 threaded through a supporting block 109, pivoted to the slotted arm 102, at 110. The screw 108 may be provided at its lower end with a handle 111, by which it may be rotated to move the adjustable connection 104 along the slot 103.

As best shown in Figs. 1, 3 and 4, the shaft 94 is provided with a pair of crankarms 115 fixedly secured thereto and connected at their free ends by links 116 with the forward ends 117 of reciprocating rods 118 extending through bearings 119 and connected at their rearward ends with the spill plate structure 17.

It will be apparent that the adjustable connection between the arm 105 and the slotted link 102 provides, in effect, a device similar to the well-known Stevenson link, whereby the amount of reciprocation imparted to the shaft 94 from the shaft 98 by this linkage may be varied from maximum to zero.

In a device such as herein illustrated, the maximum travel to be imparted to the spill plate might well be in the vicinity of four inches and accordingly the arm 107 is provided at its free end with a pointer or indicator 113, and a cooperating scale 114, marked from zero to four to indicate the amount of travel being imparted to the spill plate mechanism through this linkage, is provided on the casing side wall 33.

The slotted arm 102 may be swung about its pivotal connection 102a on the triangular arm 100 by means of the threaded bolt 120, which is pivotally connected at 121 to the free end of the slotted arm and has its other end threadedly received in a rotatable nutlike member 122 retained between a pair of spaced lugs 123 and 124, carried by the triangular arm 100. It will be apparent that rotation of the nut 122 on the threaded rod 120 will move said rod and the free end of the slotted arm 102 to vary the position of the latter, and hence of the adjustable connection 104, forwardly or rearwardly of the shaft 98. Adjustment of the slotted arm 102 with respect to the arm 100 has the effect of changing the location of the path of travel of the spill plate 17 with respect to a vertical plane passing through the axis of rotation of the rotary impeller. For example, with the Stevenson link mechanism adjusted for a spill plate stroke of two inches, positioning of the arm 102 with respect to the arm 100 in the position shown in Fig. 2, will result in the two-inch movement of the spill plate being at the forward limit of its maximum four-inch path of travel while, if the slotted arm is moved to the other extreme of its adjustment with respect to

the arm 100, the two-inch movement of the spill plate will be at the rearwardmost limit of its maximum four-inch travel. Obviously, any intermediate adjustment of the slotted arm with respect to the triangular arm 100 will produce a corresponding change in the front-to-rear location of the path of travel of the spill plate.

In Figs. 8 and 9 there is illustrated a modification of the construction heretofore described, and differing therefrom in that the spill plate is made as a plurality of separate elements 130, 131 and 132. In order that each of these spill plate elements may operate out of phase with the adjacent elements, they are provided with driving linkage substantially identical to that used to impart reciprocatory motion to the rams 13, 14 and 15, as previously described and as illustrated in Figs. 1 and 3.

The same previously-described mechanism is used to impart variable oscillatory movement to the shaft 134 (Fig. 9), which shaft corresponds in function to shaft 94 of the previously-described construction, this shaft 134 operating through the crankarm 115, link 116 and rod 118 to impart the desired motion to the first spill plate element 130, as in the previously-described modification.

A vertical shaft 135 has fixedly mounted thereon a double arm lever 136 whose one end is connected by linkage 137 to the forward end of the rod 118 with the result that the movement imparted to the rod 118 by the previously-described mechanism transmits to the opposite end of the double arm 136 a corresponding movement, but in the opposite direction, which movement is imparted to the second spill plate element 131 by the link 138 connecting said opposite end of the double arm 136 to the forward end of the rod 139, which is carried by the spill plate element 131.

A crankarm 141 is likewise fixedly secured to the vertical shaft 135, and extends rearwardly therefrom at substantially right angles to the double arm lever 136, the free end of the crankarm 141 being pivotally connected at 142 to one end of a connecting link 143 whose other end is pivotally connected at 144 to a corresponding crankarm 145, fixedly secured on a vertical shaft 146. This latter shaft has fixedly secured thereon a crankarm 147 whose free end is connected by the links 148 to the forward end of the rod 149, carried by the third spill plate element 132. It will be obvious that this linkage provides for forward movement of the intermediate spill plate element 131 when the two adjacent elements 130 and 132 are moving rearwardly, in exactly the same manner as the three rams 13, 14 and 15.

While Fig. 8 shows the linkage for driving the rams and the spill plate elements in identical positions with the result that the rams appear to be following the movement of the aligned spill plates, it should be remembered that such relation of rams and spill plates, if it occurs, will occur only momentarily inasmuch as the spill plates are preferably arranged to reciprocate at a much slower speed than the rams. This will be clear upon consideration of Fig. 1, where the sprocket 93 is shown as having fourteen teeth. If it is assumed that one complete oscillation of the shaft 86, carrying the bevel gear segment 85 and driven by the mating bevel gear segment 69, causes each of the pawls 90 and 91 to move the sprocket by the pitch of one tooth, then the sprocket will make one complete revolution for each seven oscillations of the vertical shaft 70 carrying the bevel gear segment 69 and driving the sprocket. In other words, the spill plates will operate at

one-seventh the speed of the rams. Obviously, any desired speed ratio of spill plates to rams may be obtained by change in the number of teeth on the sprocket 93, or by having the pawls 90 and 91 engage a greater number of teeth during each movement thereof.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. Stoker fuel-feeding mechanism comprising a hopper; a ram box adapted to receive fuel from the hopper; ram structure operable to push fuel rearwardly from the ram box; spill plate structure disposed rearwardly of the ram box and adapted to have fuel pushed rearwardly thereover by the ram structure for gravitational discharge over the rear discharge edge of said spill plate structure; an impeller rotatable about a horizontal axis disposed beneath the rear discharge edge of the spill plate structure and adapted to impel rearwardly fuel gravitationally fed thereto from said spill plate rear discharge edge; a stoker engine for reciprocating the ram structure; and power transmitting mechanism through which said engine imparts longitudinal reciprocatory motion to the spill plate structure to vary the longitudinal position of the spill plate rear discharge edge with respect to the rotary impeller therebelow, whereby the trajectories of fuel leaving the rotary impeller are varied, said power transmitting mechanism including means for varying the length of the path of travel of the spill plate structure and for varying the location of such path of travel longitudinally.

2. Structure as specified in claim 1, wherein said last-mentioned means includes a first oscillatable shaft, a first arm fixedly mounted thereon, a second arm pivotally connected at one end to the free end of the first arm and having an arcuate slot extending generally longitudinally thereof, means for adjusting the slotted arm with respect to the first arm about its pivotal connection therewith to vary the position of the free end of the slotted arm with respect to the axis of the oscillatable shaft, a second oscillatable shaft, a third arm fixedly mounted on the latter, link means connecting the third and second arms and including a pivotal connection slidable along the slot, and means for moving said pivotal connection along the slot.

3. In a stoker, a ram box adapted to receive fuel; a plurality of rams disposed in side-by-side relation in the ram box for longitudinal reciprocatory movement therein to feed fuel rearwardly therefrom; a plurality of spill plates disposed rearwardly of the rams and adapted to have fuel pushed rearwardly thereover by said rams, said spill plates having transversely-extending rear discharge edges from which fuel is adapted to be gravitationally discharged; a fuel impeller positioned beneath the rear discharge edges of the spill plates for rotation about a horizontal transversely-extending axis and adapted to impel fuel rearwardly as it is gravitationally discharged from the spill plates thereabove; and means for imparting reciprocatory motion to the rams and to the spill plates, with reciprocation of the latter out-of-glass with reciprocation of the former, the 75 last-mentioned means including a power-oper-

ated shaft and a driving connection therefrom to the rams and to the spill plates, said driving connection including linkage producing out-of-phase movement of one ram with respect to another.

4. In a stoker, a ram box adapted to receive fuel, ram structure disposed in said ram box for longitudinal reciprocatory movement therein to feed fuel rearwardly therefrom, a plurality of spill plates disposed rearwardly of the ram structure in side-by-side relation and adapted to have fuel pushed rearwardly thereover by said ram structure, said spill plates having transversely-extending rear edges over which fuel is adapted to be discharged, a fuel impeller positioned beneath the rear discharge edges of the spill plates for rotation about a horizontal transversely-extending axis and adapted to project fuel rearwardly as it falls thereto from the spill plates thereabove, and means for imparting reciprocatory motion to the spill plates with the motion of each spill plate out-of-phase with respect to that of adjacent spill plates.

5. In a stoker, a ram box adapted to receive fuel; a plurality of rams disposed in side-by-side relation in the ram box for longitudinal reciprocatory movement therein to feed fuel rearwardly therefrom; a plurality of spill plates disposed rearwardly of the rams and adapted to have fuel pushed rearwardly thereover by said rams, said spill plates having transversely-extending rear discharge edges from which fuel is adapted to be gravitationally discharged; a fuel impeller positioned beneath the rear discharge edges of the spill plates for rotation about a horizontal transversely-extending axis and adapted to impel fuel rearwardly as it is gravitationally discharged from the spill plates thereabove; and means for imparting reciprocatory motion to the rams and to the spill plates, with reciprocation of the latter out-of-phase with reciprocation of the former, the last-mentioned means including a power-operated shaft and a driving connection therefrom to the rams and to the spill plates, said driving connection including linkage producing out-of-phase

movement of one spill plate with respect to another.

6. In a stoker, a ram box adapted to receive fuel; a plurality of rams disposed in side-by-side relation in the ram box for longitudinal reciprocatory movement therein to feed fuel rearwardly therefrom; a plurality of spill plates disposed rearwardly of the rams and adapted to have fuel pushed rearwardly thereover by said rams, said spill plates having transversely-extending rear discharge edges from which fuel is adapted to be gravitationally discharged; a fuel impeller positioned beneath the rear discharge edges of the spill plates for rotation about a horizontal transversely-extending axis and adapted to impel fuel rearwardly as it is gravitationally discharged from the spill plates thereabove; and means for imparting reciprocatory motion to the rams and to the spill plates, with reciprocation of the latter out-of-phase with reciprocation of the former, the last-mentioned means including a power-operated shaft and a driving connection therefrom to the spill plates, said driving connection including Stevenson linkage for varying both the length and location of the travel of said spill plates.

Certificate of Correction

Patent No. 2,487,464

November 8, 1949

DONALD J. MOSSHART

It is hereby certified that error appears in the printed specification of the above numbered patent requiring correction as follows:

Column 6, line 74, for "out-of-glass" read *out-of-phase*;
and that the said Letters Patent should be read with this correction therein that the same may conform to the record of the case in the Patent Office.

Signed and sealed this 28th day of February, A. D. 1950.
